UNITED STATES PATENT OFFICE.

ALBERT L. WHITE, OF YUMA, ARIZONA.

DESIGN FOR A PENDANT.

Application filed September 13, 1923. Serial No. 7,193. Term of patent 3½ years.

To all whom it may concern:

Be it known that I, ALBERT L. WHITE, a citizen of the United States, residing at Yuma, in the county of Yuma and State of Arizona, have invented a new, original, and ornamental Design for a Pendant, of which the following is a specification, reference being had to the accompanying drawing, forming part thereof.

The figure is a front elevational view of a pendant member showing my new design.

I claim:

The ornamental design for a pendant, as shown.

ALBERT L. WHITE.
